(57) **CLAIM**

The ornamental design for a camping tent as shown and described.

DESCRIPTION

FIG. 1 is a front, right and top perspective view of the inner tent of the camping tent, showing our design.

FIG. 2 is a rear, left and bottom perspective view of the inner tent of the camping tent in FIG. 1.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, right and top perspective view of the outer tent of the camping tent.

FIG. 10 is a rear, left and bottom perspective view of the outer tent of the camping tent in FIG. 9.

FIG. 11 is a front elevation view thereof.

FIG. 12 is a rear elevation view thereof.

FIG. 13 is a left side elevation view thereof.

FIG. 14 is a right side elevation view thereof.

FIG. 15 is a top plan view thereof.

FIG. 16 is a bottom plan view thereof.

FIG. 17 is a perspective view of the assembly of the inner tent and outer tent of the camping tent; and,

FIG. 18 is a perspective view of the assembly of the inner tent and outer tent of the camping tent.

The broken lines shown in the drawings are included for the purpose of illustrating portions of the camping tent that form no part of the claimed design.

1 Claim, 18 Drawing Sheets
